ROLLING MACHINE

Leonard Bayliffe Henderson, Olton, England

Application June 25, 1947, Serial No. 756,841

Claims priority, application Great Britain
June 29, 1946

1. Claim. (Cl. 80—35)

1 This invention relates to rolling machines particularly of the type comprising a plurality of roll stands, such as, for successively shaping or working a strip or length of metal. Ordinarily all the rolls are geared together so that the drive is transmitted from or through one roll set to another and many objections are thereby presented. The present invention has for its object to provide means for readily assembling and disassembling the vital parts of a rolling machine in which a roll set or stand can be displaced without interfering with the drive to other roll sets, so that such operations taking place on one passage of the work-piece through the machine, can be considerably varied.

According to the present invention, the rolling machine is provided with a machine bed frame having a substantially horizontal top surface, a drive shaft mounted in bearings above, centrally of said surface and longitudinally thereof, worm gears seated on said drive shaft and at intervals therealong, and a roll stand forming a unitary structure detachably mounted on the surface of the machine bed frame, the stand supporting by means of roll shafts the rolls adapted to be detachably coupled with a worm gear on the longitudinal shaft by means of a worm wheel seated on one of said roll shafts, and means registering the roll stand on the aforesaid top surface so that the worm wheel on the roll stand will mesh with the worm gear on the longitudinal drive shaft. Thus, all roll stands are automatically positioned in alignment with each other. The arrangement is conveniently carried out so that when the roll stand is correctly positioned and registered on the bed frame, the gearings (worm and worm wheel) are simultaneously placed into intermeshing engagement.

A worm on the longitudinal shaft is adapted to mesh with a worm wheel on a roll shaft mounted on the roll stand. The bed frame and the roll stand frame have, respectively, interfitting formations in the form of projections and recesses or grooves to register the roll stands in correct alignment with each other and in correct position to the bed frame to ensure meshing of the aforesaid gearings. The roll stands are interchangeable with stands for effectuating welding, punching or like operations.

Each roll stand is thus driven independently from a driving member which may comprise a single drive shaft extending longitudinally along the row of roll stands. With this arrangement the drive for one roll set has not to be passed through the drive of another roll set, thereby

ensuring that undue strain is not placed on the driving gear. The drive shaft is geared to the roll shafts in such a manner that any roll stand can be removed when required, without interfering with the working of the other roll sets.

Any other type of machine such as for perforating, shearing or welding the workpiece may be substituted for a roll stand and such machine driven from the drive shaft or by separate means, thereby enabling any desired sequence of operations to be effected on one passage of the work-piece, through the machine.

In order that the invention may be clearly understood and readily carried into effect, reference may be had to the accompanying drawings, in which:

Figure 1 is a side elevation of a rolling mill constructed according to this invention, and Figure 2 is a front elevation of a portion of the machine.

According to one form of the invention, a longitudinal driving shaft 1 is mounted in pedestal bearings 2 fixed on a bed frame 3 and worm gears 4 are mounted on this horizontally arranged shaft at predetermined intervals therealong. The bed frame 3 and driving shaft 1 and gear 4 thereon thus constitute a unitary structure. Roll stands A each of which is self-contained, are detachably mounted on the bed 3, such stands comprising frames having side members 5 in which are mounted a pair of roll shafts, the lower roll shaft 6, between the side members 5 carrying a worm wheel 7 splined to said lower roll shaft, which worm wheel 7 meshes with a worm 4 on the drive shaft 1. Both roll shafts of a pair are mounted in journal blocks carried by the side members 5 and the upper roll shaft 8 is normally free to rotate in the journals so that the upper roll can be non-rotatably fixed on the shaft. The roll stands A are fixed on the bed 3 by holding down bolts, and the foot or bottom foot of each side member 5 has a slot or mortise 9 for engaging a tenon 10 on the bed to correctly position the roll stands in alignment and in correct position for the meshing of the worm 4 and worm wheel 7. Thus any number of roll stands can be arranged over the drive shaft 1 and any particular roll stand can be readily removed without affecting the operation of the other roll stands. The roll stand A is thus a unitary construction incorporating gearing for transmitting the drive to the roll shaft from the driving shaft, and when the roll stand is positioned on the bed frame 3, the gearing on the two unitary structures are simultaneous-

ously placed in mesh. The side members 5 of each stand are inter-connected by the cross member or web 5a at a level above the lower roll shaft 6 and such web has a hole 5b therein for anchoring a lifting device thereto by means of which the roll stand may be removed in vertical movement whereby said worm wheel is brought out of mesh with its worm with inherent disengagement from its worm drive. In place of a roll stand any other machine can be fitted and arranged to be driven from a worm on the drive shaft, for instance a strip of metal can be perforated, rolled into a tube and the joint welded in a single "pass" through the machine. The upper roll of a pair is free to roll on its own pitch circle but when necessary the two shafts of a pair may be geared together so that the upper roll is driven, which arrangement may be required at the finishing end to assist in pulling the work through the "pass." Rolls may be mounted on one or both ends of the roll shafts projecting laterally from the roll stand.

Having thus described the invention, what is claimed as new and desired to be secured by Letters Patent, is:

A rolling machine comprising a bed having a top surface, spaced bearings seated on said top surface, a single driving shaft supported at spaced points by said bearings, mortise or tenon means on said surface at each side of said shaft and between said spaced bearings, a worm disposed between said spaced bearings and mounted for drive on said shaft, a self-contained roll stand forming a unitary structure detachably mounted on said top surface, said stand comprising a pair of upright side members one on each side of said shaft and each having a bottom foot provided with mortise or tenon means interfitting corre-

spondingly with those of said surface for engagement upon vertical assembly movement, upper and lower roll shafts extending across and beyond said side members, journals in said side members for said roll shafts, whereby the latter have respective ends projecting beyond both said side members for mounting rolls thereon, reinforcing means extending between said side members and interconnecting the latter at a level above said lower roll shafts so that an open space is provided between said bottom feet of said side members and directly above said driving shaft and said lower roll shaft, a worm wheel splined to the lower roll shaft and positioned intermediate said side members and engaging said worm of said driving shaft, the interfitting tenon and mortise means and the position of said worm and said worm wheel, which allow for vertical movement of said worm wheel out of mesh with its worm being such that said self-contained roll stand may be vertically removed with inherent disengagement from its worm drive.
